United States Patent Office

Des. 185,501
Patented June 16, 1959

185,501

MOTION-PICTURE CAMERA

Frederick G. Knowles, Rochester, N.Y., assignor to Eastman Kodak Company, Rochester, N.Y., a corporation of New Jersey

Application January 26, 1959, Serial No. 54,303

Term of patent 7 years

(Cl. D61—1)

Fig.1

Fig.2

Fig. 3

Fig. 4

Fig. 1 is a perspective view of a motion-picture camera embodying my new design and showing the viewfinder elements in their erected position;

Fig. 2 is a top plan view thereof showing the viewfinder elements folded down onto the camera case;

Fig. 3 is another perspective view thereof showing the sides opposite those shown in Fig. 1; and

Fig. 4 is a bottom plan view thereof.

The dominant features of my design reside in the portions shown in full lines.

I claim:

The ornamental design for a motion-picture camera, as shown and described.
